Both men, DeMolay and his son, had been present when
the first and second degrees were given to the first members
of the Lodge. They were the first to be initiated into the
Order. Both men were present when the first members
of the Lodge were initiated into the Order. Both men
were present when the first members of the Lodge were
initiated into the Order.

UNITED STATES PATENT OFFICE

2,566,429

**DISPENSING VALVE FOR SURFACE COATING
MOPS, HAVING A CORD OPERATED VALVE
ACTUATING LEVER**

Solomon Schulman, New York, N. Y.

Application December 31, 1946, Serial No. 719,503

3 Claims. (Cl. 222—501)

1. *What is the relationship between the two concepts?*

ates to surface coating, or wax co-

This invention relates to surface coating, especially the coating of floors and furniture and more particularly the waxing thereof.

A principal object of this invention is the provision of a device to facilitate the preliminary deposit onto a surface of a fluid which is to be thereafter spread and/or polished.

A further object of the invention is the production of a device of the type specified by which the initial or preliminary deposit of a fluid onto a surface to be coated may be accomplished by a simple manual motion adjacent the point where the device used for polishing is grasped.

A further object of the invention is the production of a device of the type specified which will include alternative means for depositing a fluid on a surface to be coated.

Other objects and advantages will appear as the description of the particular physical embodiment selected to illustrate the invention progresses and the novel features will be particularly pointed out in the appended claims.

In describing the invention in detail and the particular physical embodiment selected to illustrate the invention, reference will be had to the accompanying drawings and the several views thereon, in which like characters of reference designate like parts throughout the several views, and in which:

Fig. 1 is a side elevational view of a polishing mop embodying my invention shown with the polishing end thereof resting upon a surface to be polished; Fig. 2 is a front elevational view of the device as shown by Fig. 1; Fig. 3 is a cross sectional view of the device on the plane indicated by the line III—III of Fig. 2 viewed in the direction of the arrows at the ends of the line; Fig. 4 is a cross sectional view on the plane indicated by the line IV—IV of Fig. 2, viewed in the direction of the arrows at the ends of the line; Fig. 5 is a fragmentary view of a modified form of polishing mop embodying my invention; Fig. 6 is a view similar to Fig. 5 of a modified form of polishing mop embodying my invention; Fig. 7 is a fragmentary view illustrating a modified form of polishing fluid container orifice valve means.

Numerical 1 designates an operating handle of an ordinary and well known form of coating or polishing mop. The handle 1 carries at its extreme end a mop head 2 of any suitable, appropriate or ordinary textile or other material efficient in spreading and polishing a coating fluid, such as wax, on a surface, such as a floor or furniture.

3 designates any usual or ordinary coating fluid

or wax containing receptacle customarily used in dispensing. Container 3 may be provided with any of the usual or ordinary orifices, such as the projecting neck or spout 4, as best shown in Fig. 5. This neck 4 is usually made of thin material and is usually rolled into the form of a screw thread as shown in Fig. 4. Alternatively the projection 4 may be plain as in Fig. 7.

When the container 3 is purchased it is provided with a cap closing the orifice. In accordance with my invention, that cap is removed and my improved valve means are substituted therefor, as best shown in Fig. 4. The valve means includes a cap piece 5 having a depending skirt 6 which is rolled into the form of a thread corresponding with the thread upon 4, so that my valve means may be screwed upon the orifice or spout 4. The face of the cap 5 is orificed at 7 and 8, best shown in Fig. 3, and the orifices are closed by a valve disk 9, best shown in Fig. 4. When the container is in the position as shown in Fig. 2 and the valve disk 9 is raised, fluid may flow through the orifices 7 and 8, and as shown in Fig. 1, and may drop upon the surface or floor 10 which it is desired to coat or polish.

The valve disk 9 has an eyelet 11 therethrough, and a washer 12 attached thereby to the valve disk 9. The valve rod 13 is driven into the eyelet 11 and then headed as at 14 so that the valve rod 13 is securely held to the valve disk 9. In order to guide the valve rod 13, I position a valve rod guide or U-shaped stirrup, 15 on the valve cap 5. This valve rod guide 15 is generally in the form of a U with the extremities of each leg bent at a right angle as at 16 and each extremity attached to the valve cap 5, as by soldering or other suitable method. The bent over portions of the extremities of the legs of the U are made to extend over the edge 17 of the cap 5 for a purpose to be later specified.

The valve rod guide 15 is orificed as at 18 in the portion connecting the legs and through this extends the valve rod 13.

The end of the valve rod, in the form shown in Figs. 1 to 4 inclusive, is formed into an enlargement or eye 19. Between the eye 19 and the valve guide 15, a spring 20 is positioned. This spring normally forces the valve rod 13 downwardly, as viewed in Fig. 4, so that the valve disk 9 is seated firmly against a flat disk valve seat 21 resting on the inner side of the valve cap 5 and orificed to correspond with orifices 7 and 8.

As best shown in Fig. 2, a valve fulcrum 22 is attached to the valve guide 15 by an eyelet 23.

This fulcrum 22 has an orifice at 24 and engaged in this orifice is one end of a valve lever 25. The valve lever 25 extends through the eye 19 in the valve rod 13 and on its far end is suitably and properly formed as by making an eye therein 26 into which may be engaged an operating means, such as a cord 27, which may extend upwardly a desired distance to be closely adjacent that portion of the handle 1 grasped by a person in operating the mop.

In order to sustain the container 3 in a position on the mop handle, I provide a clamp or container support 28. This clamp is preferably formed of two pieces of rectangular cross section metallic material riveted together at 29, and, as viewed in Fig. 3, to the left of the riveted portion the separate pieces 30 and 31 are bowed so as to form a somewhat circular opening therebetween to receive the mop handle 1 and their extreme ends are orificed to receive a bolt 32 having, preferably, a wing nut 33 thereon by which the pieces 30 and 31 of the support may be securely attached to the handle 1 at any desired position along its length.

The support 28 to the right of the rivet 29, as shown in Fig. 3, has the two pieces 30 and 31 likewise bowed, so as to form a space 34 to receive the can orifice or spout 4 and the extreme right hand ends are orificed to receive a bolt 35 having, preferably, a wing nut 36 thereon whereby the container may be tightened about the orifice 4.

It will be noticed that the right angle extensions 16 of the U-shaped valve stem guide 15 extend over the member 28, as best shown in Figs. 2 and 3, so that the member 28 is prevented from slipping off the can orifice 4 even if wing nut 36 is not completely tight.

By the above construction I provide means whereby a container 3 may be held in a desired position on a mop handle 1 and whereby, by operating the cord 27 I may open the valve by unseating disk 9 and allowing fluid to flow from the container onto a surface to be polished and that this may be done by the device, cord 27, which is closely adjacent the point where the handle 1 is usually grasped in operating the device.

In Fig. 5 I have shown a modification of the device, in that the valve stem has been modified so that the valve stem 37 is straight throughout and has a bulbous member 38 on its extreme end, the spring 20 being positioned between the bulbous member 38 and the valve stem guide 15. In this form of the device, the container is attached to the rod 1 in such a position that the bulbous portion 38 is closely adjacent the surface being worked upon, so that if the rod 1, as shown in Fig. 1, is brought to a vertical position the bulbous portion 38 will touch the floor or surface being worked upon, opening the valve and allowing fluid to flow from the container 3.

In Fig. 6 I have shown a further modified form in that I form an eye in the form of a loop 39 in the valve stem corresponding to the eye 19 of Fig. 4. The material of the valve stem is continued beyond the rod, as at 40, and on its continuation or extension a bulbous member 38 is positioned. This form is a combination of the two forms as shown in Figs. 1 to 4 inclusive and Fig. 5. In the form shown by Fig. 6 the valve may be opened by pulling upon the cord 27 or by raising the handle to a vertical position and causing the bulbous member 38 to contact the surface being worked upon.

In Fig. 7 I have illustrated the possibility of using another form of attaching means for the valve structure. The orifice 41 corresponding to orifice 4 of Fig. 4 is not formed into a screw thread, but is somewhat plain and the valve means are attached thereto by forcing the cap 42 on to the surface 41 and then tightening it thereon by the lever 43, which draws the wire 44 tightly around the neck 41. This form merely illustrates that, instead of using a screw cap valve structure, other forms may be used.

Although I have particularly described particular physical embodiments of my invention, nevertheless I desire to have it understood that the forms selected are merely illustrative and do not exhaust the possible physical embodiments of the idea of means underlying my invention.

What I claim as new and desire to secure by Letters Patent is:

20. 1. A coating device, including, in combination: a container formed with a projecting spout; a valve cap positioned over the projecting spout, said valve cap formed with orifices therethrough to allow fluid to flow therethrough, a valve disk 25 within the cap positioned over the said through orifices; a valve rod attached to the valve disk and projecting through the top of the cap; a valve rod guide formed substantially in the form of a U with the extremities of the legs of the U each bent at a right angle and attached at the right angle to the cap, said U formed with a through bore in the portion of the U connecting the legs through which the valve rod extends; an enlargement formed on the outer end of the valve rod; a spring 35 between the said enlargement and the valve rod guide whereby the valve disk is held seated within the cap to prevent flow of liquid therefrom; a valve fulcrum attached to the valve rod guide and extending to a point adjacent the enlargement on the valve rod; a valve lever fulcrummed at one end of the valve fulcrum and engaging the enlargement of the valve rod and projecting therebeyond; and a flexible member attached to the extreme end of the valve lever and adapted to extend up along the handle of a mop to a position adjacent the usual grasping position of an operator when operating the mop whereby the valve may be opened by a pull on the flexible member.
50. 2. A coating device, including, in combination: a container formed with a projecting spout; a valve cap positioned over the projecting spout, said valve cap formed with orifices therethrough to allow fluid to flow therethrough; a valve disk 55 within the cap positioned over the said through orifices; a valve rod attached to the valve disk and projecting through the top of the cap; a valve rod guide formed substantially in the form of a U with the extremities of the legs of the U each bent at a right angle and attached at the right angle to the cap formed with a through bore in the portion of the U connecting the legs through which the valve rod extends; an eye 60 formed in the valve rod; a spring between the said eye and the valve rod guide whereby the valve disk is held seated within the cap to prevent flow of liquid therefrom; a valve fulcrum attached to the valve rod guide and extending to a point adjacent the eye in the valve rod; a valve lever fulcrummed at one end of the valve fulcrum and projecting therebeyond; and a flexible member attached to the extreme end of the valve lever and adapted to extend up along the handle of a mop to a position adjacent the usual grasping posi-

tion of an operator when operating the mop whereby the valve may be opened by a pull on the flexible member.

3. A hollow fluid storage and delivering container, formed with an outlet orifice provided with an open projecting spout; a cap adapted to be secured upon the projection, the top of the cap being orificed at a plurality of places; a valve disk within the cap covering the said orifices, the said disk formed with a through bore; a valve rod positioned in the bore of the valve disk and secured thereto; a U-shaped stirrup attached to the top of the cap at the outside, said stirrup formed with a through bore for the reception of a rod whereby the rod is guided; an eye formed in the valve rod; a spring between the said eye and the stirrup whereby the valve is retained closed; a bulbous member positioned on the valve rod beyond the eye therein; means, including a double clamp, one portion surrounding the cap and the other portion surrounding the mop handle for supporting the container in position on the mop handle; a projection extending from the stirrup; a valve actuating lever fulcrumed on the projection and passing through the eye of the

valve rod; a flexible member attached to one end of the valve lever and extending along the handle to a position adjacent the position of the hand of an operator in usual operation whereby the fluid may be allowed to flow from the container either by a pull on the flexible member or by causing the bulbous member to bear against the surface to be coated.
